UNITED STATES PATENT OFFICE

JOHN FRAZER WARNER, OF MUNCIE, INDIANA

GARAGE DOOR

Application filed August 5, 1929. Serial No. 383,479.

This invention relates to flexible doors intended for garages or other buildings having large or wide doorways. A door of this type consists of panels hingedly connected together, and which are retained movably in runways therefor in such manner that the door may assume a status other than vertical as it is raised from the lower or closed position and to an overhead open position. A counterbalancing mechanism is so constructed and arranged that jarring or slamming of the door is prevented, and the door is capable of being easily moved to, and it is safely retained, in any adjusted position.

In the art as now understood, the counterbalancing mechanism is arranged in position either above the door and housing structure proper, or within the housing frames or jambs of the door. Such arrangements involve the use of mechanical parts more or less detached, and space for them is required either above or below the door structure. The parts of such mechanisms are not easily assembled or installed, nor are they easily accessible for purposes such as inspecting, adjusting or repairing. Moreover there is not the desired ease of actuation of the door at the beginning of its movement toward either the open or the closed position.

To accomplish improvements in construction whereby the above objections may be overcome, and to provide a door which is capable of being easily and economically handled in the manufacture, the transportation and the installation thereof, and which said door is self contained, and durable, and dependable, and easy to operate, are the objects of my invention.

The above named general purposes as well as more specific aims of my invention, as will appear as the specification of my invention proceeds, are accomplished by the new construction, combination and arrangement of parts described in the following specification. The several parts of my invention as they appear in the accompanying drawings, are identified by suitable characters of reference.

Figure 1 is a front view of my improved door construction.

Figure 2 is a top plan view of Figure 1.

Figure 3 is an enlarged rear view of Figure 1.

Figure 4 is a top plan view on line 4—4 in Figure 1.

Figure 5 is an enlarged vertical sectional view taken on the line 5—5, and as seen in the direction of arrow 5 in Figure 1.

Figure 6 is an enlarged detail view of the end portion of the lowermost door panel.

Figure 7 is an enlarged detail view of the hip portion of one of the housing units, this view being taken on the line 5—5 in the direction of the arrow 5 in Figure 1.

Figure 8 is a sectional top plan view taken on line 8—8 in Figure 6.

Figure 9 is a sectional top plan view taken on line 9—9 in Figure 7.

Figure 10 is a sectional top plan view (enlarged) taken on line 10—10 in Figure 5.

Figure 11 is a vertical cross section view taken on line 11—11, in the direction of arrow 11 in Figure 6.

My invention provides spaced opposed upright housings, guide and runway units having curved hip portions and parallel horizontal portions, the runways of which said units are confronting, a door consisting of panels flexibly connected together and having their ends retained movably in said housings, antifriction bearings on the end portions of said panels, and which are operable in said runways, a tension device carried by the door, and flexible connections between the said tension device and the housings whereby the door is counterbalanced in all of its positions.

In the embodiment of my invention as shown in the drawings I have illustrated the several features and details of construction, in the form and arrangement deemed preferable, it being obvious that they may be modified and varied within the scope of the invention as defined by the appended claims. The present structure has a height over all of about ten feet, and a width of about eight feet, and is intended especially for the doorways of garages. The height of the door is about eight feet.

The housing and runway units are of right

- and left formation. Each comprises an upright section, a curved hip section and a horizontal section. Each of the upright sections and horizontal sections, consists of a relatively light sheet metal plate, of suitable predetermined width, made into formation in cross section as shown in Figure 10, to constitute a housing and guideway 1, having the face plate 2 and a runway 4 with inturned flange 5. At a suitable distance from the approximate ends of these sections, the runway portions thereof are cut away, thereby constituting abutment faces 6 and 7 indicated in Figure 7.
- 15 The hip section consists of a stout gusset plate 8, of right-angle formation, and which is provided with a curvilinear flange 9 with inturned lip 10. Flanges 11 of the right-angle edge portions are adapted to be secured by bolts or rivets to the flanges 1a of the upright and flanges 1a of the horizontal sections of the housing. The several sections thus constituting the housing unit are firmly united, and the flange 9 constitutes a runway from the lines of jointure 6 and 7. The said housing units are retained at spaced distance apart by having their foot portions suitably anchored to the floor, and by having their upper portions stayed by a head plate 12, and by the suitable cross plates 13 and 14. After the housing structure just described will have been set up in the doorway space, the end portions of the horizontal sections are stayed by suitable braces or stay pieces 35 (not shown) which extend to some part of the superstructure of the building.
- 40 The door panels, in the present instance four in number, and designated 15, 16, 17 and 18, and which are connected together by the suitable hinges 20, are adapted to occupy position with their ends immediately at the rear of the face plates 2 of the housing units. At the rear side of each of the upper corners of the panels 16, 17 and 18, and at the rear side of each of the four corners of the lowermost panel 15 is a bracket 21. Retained in adjusted position in the longitudinal bore of said bracket by set nuts 22 is a spindle 23, upon which is journaled a roller 24. The 45 relative positions of the several parts just described are shown in Figure 11, the rollers being operable freely in the runways 4, and being guarded against displacement by the flanges 5.
- 50 55 On one of the door panels, in the present instance the panel 15, complementary tension devices are carried. These tension devices are similar in construction, function and capacity, and each consists of a helical retractile spring 30, one end of which is secured to the panel, and the other end being provided with stirrup 31 in which is journaled a sheave 32.
- 60 On a suitable spindle 33 provided on the rear side of the panel 15 and near its end, is journaled a grooved pulley 34. On a spindle

block 35 provided therefor on the lower portion of each end of said panel, there is journaled the relatively small grooved pulley 36. At a suitable height, and located in the position as shown in Figure 7, an eyelet 37 is secured. At the suitable locations as shown in Figure 3 and in Figure 6, adjacent to the pulleys 34, are secured the eyelets 38.

70 Cables 40, each having an end secured to an eyelet 38, are trained over the sheaves 32, the pulleys 34, the pulleys 36, and thence upwardly to the eyelets 37 of the housing unit, where they are secured. The length of each cable is such that with the door panels in the vertical status (the door being closed) the springs 30 are expanded as shown in Figure 3, there being stored and retained thereby a tension of such degree that by the application of a slight lifting effort the door may be raised, the same being counterbalanced. The counterbalancing effect of the device is constant, the tension on the springs being diminished as the door proceeds on its upward travel.

75 Advantages of my invention are the extreme compactness and simplicity of the construction, the substantial strength of the structure in its entirety, the accessibility of the several parts, and the elimination of the necessity of a counterbalancing part, either above or below the housing units. The face plates of the housings constitute effective closures for sides of the door against the elements. The runways are at such position, removed from the housing portion of the unit, that they are easily accessible for any purpose, and being flanged they also function as guides to prevent the rollers from deviation from a straight course. Moreover there is easy access to the bearings of the rollers for the necessary occasional lubrication thereof. Light sheet metal cover plates 42 on the rear side of panel 15 suitably enclose the springs 30 and their several connections.

80 85 90 95 100 105 110 115 120 125 130 A latching and locking device for the door may consist of guides 44 on the ends of one of the door panels, and in which are retained slide bolts 45 that are adapted to enter suitable openings provided therefor in the housings. The said bolts are retracted by rods 46 which are pivotally connected to a head 47, rotatably mounted on the door panel. The said head 47 is provided with a crank 48, and by which it may be easily actuated, and which said crank is capable of being held to a stop lug 49 by a padlock.

90 95 100 105 110 115 120 125 130 The invention in readiness to be installed, consists of the upright sections, the horizontal sections, and the hip sections, the cross plates 12, 13, and 14, and the door (one of said panels having the tension devices thereon) and the cables. The several parts referred to are each capable of being manufactured and handled and transported economically, and in turn they are capable of being easily assembled and installed. The inven-

tion is applicable for doors for buildings of all kinds, and for doorways of various dimensions. Variations in the degree of tension desired to compensate for variations in height of the housing units, and for variation in number, size and weight of the door panels, are accomplished by variation in the tensile properties in the springs 30, and also variation, if necessary, in the dimensions of the sheaves 32, and pulleys 34 and 36. The variation of the type of rollers, whether having ordinary parallel bearings, pin bearings or ball bearings, does not involve any structural changes, as the spindles 23 are capable of being moved to and held in positions adjusted longitudinally of the door panels (the door being caused to operate in alignment by the flanged runways) whereby any possibility of sticking of the door, or interruption of its smooth and free movement, is eliminated.

I am aware that minor changes and modifications may be made in the structural features and details of my invention, within the scope of the invention as it is defined by the appended claims, without departing from the spirit of the invention or sacrificing any of its advantages.

What I claim as my invention and desire to secure by Letters Patent is:—

1. A doorway structure of the kind described, comprising spaced housing units having curved hip portions and being of formation in cross section to provide frontal cheeks and offset runways, door panels hingedly connected together and whose ends are in registration with the rear of the cheeks of said housings, rollers on the door panels and which are operable in said runways, complementary coil springs carried on the lowermost door panel one end of each spring being secured to said panel, and the other end of each spring being provided with a sheave, a pulley at each end of the rear face of said panel, a pulley on each end and near the lower edge of said panel, and cables trained through said sheaves and over said pulleys, each cable having one of its ends connected to said panel at a location adjacent to the first named pulley, and the other of its ends being connected to the hip portion of the adjacent housing.

2. In flexible door construction, comprising guide and runway housings oppositely disposed, and there being movable therein a door composed of flexibly connected panels, an expandible and retractile spring carried by and having one of its ends secured to the lowermost door panel, the other end of said spring being provided with a sheave, a pulley on one side at the upper portion and a pulley on one end at the lower portion of said panel, and a cable trained over said sheave and the said pulleys and up through the housing, one end of the cable being secured

to the said door panel at a location adjacent to the first named pulley and the other end being secured to the said housing at the upper portion thereof.

3. In a door construction comprising opposed upright housings having frontal cheeks, and embodying confronting trackways curved in their hip portions and which are thence extended rearwardly, articulated door panels having rollers operable in said trackways and their ends being in registration with the rear sides of said cheeks, a pulley on the rear side of the upper portion of each end of the bottom panel, a pulley on the lower portion of each end of the bottom panel, a pair of coil springs each having one end secured to the rear side of the bottom panel, a sheave on the free end of each of said springs, a cable of predetermined length trained over the said pulleys and said sheave, one end of said cable being fastened to the housing at its upper portion, and the other end being fastened to the rear side of the bottom panel at position adjacent to and at a plane below that of the pulley first above named.

4. A door construction comprising spaced opposed upright housings, guide and runway units having curved hip portions and parallel horizontal portions, the runways of which said units are confronting, door panels flexibly connected together and having their ends retained movably in said housings, anti-friction bearings for said panels and which are operable in said runways, complementary coil springs carried on the bottom panel, one end of each spring being secured to said panel, and the other end of each spring being provided with a sheave, a pulley at each end of the rear side of said panel, a pulley on each end and near the lower edge of said panel, and cables of predetermined length trained through said sheaves and over said pulleys, the ends of which said cables are connected to the said panels at locations adjacent to the first named pulley, and to the upper portions of the housings.
